COMBINED SHIPPING AND DISPLAY BOX FOR BOTTLED GOODS

Jerome Gould, Los Angeles, Calif., assignor to Paul Masson, Inc., Saratoga, Calif., a corporation of California

Filed Sept. 10, 1965, Ser. No. 86,936

Term of patent 14 years

(Cl. D58—26)

FIGURE 1 is a front perspective view of a combined shipping and display box showing my new design, the end opposite to that shown in the drawing being identical in appearance therewith;

I claim:

The ornamental design for a combined shipping and display box for bottled goods, as shown and described.
